REFRIGERATING APPARATUS

Ralph L. Tweedale, Washington, D. C., assignor,
by me and assignments, to General Motors Corporation, a corporation of Delaware

Application April 14, 1932, Serial No. 605,169

9 Claims. (Cl. 194—9)

This invention relates to coin controlled meters wherein timing means is provided to limit the service of the device to be metered to a predetermined period of time. It is the object of the invention to provide a metering device of the coin controlled type wherein a constantly running electrical timing motor is provided and including a mechanism for controlling the service to be metered by the insertion of a coin which initiates movement of a time determining member.

Further objects and advantages of the present invention will be apparent from the following description, reference being had to the accompanying drawings, wherein a preferred form of the present invention is clearly shown.

In the drawings:

Fig. 1 represents a front view of the timing mechanism, the clock dial being removed for purposes of clearer illustration;

Fig. 2 is a wiring diagram showing the connection of the meter to the device to be metered;

Fig. 3 is a cross-section on line 3—3 of Fig. 1; and

Fig. 4 is a cross-section on line 4—4 of Fig. 1.

In the drawings, 2 represents one of the dial gears of an ordinary clock, said gear being connected to the sleeve to which the hour hand 4 is fastened and turns therewith. Gear 2 is driven from the minute hand shaft through the gears 6, 8, and 10 constituting the gears of the dial train of an ordinary clock. The minute hand 12 is connected to the minute shaft 14 in the usual manner. The minute shaft 14 is driven from the usual clock work comprising the gear train 16 and motor 18. It is preferred that a self-starting synchronous motor clock work be used although any other type of electrically driven or spring driven clock work may be used. Secured to the hour gear 2 and in front of the same is located a gear 20 which meshes with a gear 22 above the same. The ratio between these gears may be such that the gear 22 makes one rotation during the timing period which is intended to be provided by the insertion of a single coin in the device. In the drawings a two to one reduction is represented so that the gear 2 makes one rotation in twenty-four hours, thus providing for twenty-four hours of service on the insertion of a single twenty-five cent piece. A timing arm 24 is connected to the gear 22 through a slip connection constituted by a plate 26 rigid on shaft 28 and a spring 30 which places the arm 24 in frictional engagement with the plate 26. The frictional force transmitted from the plate 26 to the arm 24 is less than the force which the clock

motor exerts at that point, but greater than the force required to rotate an arm 32 about its pivot 34 against a spring 36. The arm 32 has a nose 38 extending into the path of the outermost end of arm 24 which is offset and at the opposite end thereof carries rigidly a lug of insulation 40. Stops 42 and 44 limit the pivotal movement of arm 32 and the spring 36 connected to an extension 48 of the pivoted arm 48 holds the arm 32 normally in a position not shown in Fig. 1 with stop 44 engaging arm 48. Arm 48 carries an armature 50 adapted to be attracted by an electromagnet 52. The lug 40 co-acts with a spring contact arm 54 so that when the arm 32 is rotated counter-clockwise from the position shown in Fig. 1 to a position in which stop 44 abuts the arm 48, the contacts 56 which are normally closed are opened and the contacts 58, normally opened, are closed. A coin chute 60 is provided having a laterally offset tube to prevent tampering with the mechanism and to provide room for stacking a plurality of coins therein, a single coin 62 being shown in operative position in the chute. The arm 48 has a downward extension 64 having coin feeding arms 66 and 68 adapted to be alternately projected into the sides of the coin chute 60 through suitable openings, in the sides thereof. In the operating position of the device the coin 62 rests on the bottom lug 68 and the upper lug 66 is withdrawn from the chute. A piece of insulation 70 projects into the side of the coin chute through a suitable opening and when a coin rests in the position shown at 62 the coin forces the insulating piece 70 outwards to close the contacts 72.

The electrical parts of the device are connected so that the contacts 58 form the main switch for the device to be metered. Terminal 74 of the contacts 58 is connected to the line supplying current. Terminal 76 is connected to the device to be metered which is shown in Fig. 2 as representing an electric refrigerator of ordinary construction having a temperature controlling switch 78 and a motor 80 which drives a compressor 82 for compressing gaseous refrigerant. The compressed refrigerant may be liquefied in a condenser 84 and the liquefied refrigerant collected in a receiver 86 from which it is led to an evaporator 88 for expanding the liquid refrigerant into gaseous form whence it returns to the compressor. The temperature controlling switch may be of the low pressure control type as illustrated or may be responsive to the temperature inside the refrigerator cabinet. The other side of the switch 78 is connected to the side of the line opposite termi-

nal 14. The clock work motor 18 is connected permanently across the main current supplying line so that it is continually running as long as there is current supply from the line. Terminal 90 of contacts 56 is connected to one terminal 82 of the electro-magnet 52. The other terminal 94 of the electro-magnet 52 is connected to terminal 96 of contacts 72 while terminal 98 of contacts 72 is connected to the opposite side of the line from the terminal 14. It will be seen that there is thus provided an external circuit for the refrigerator to be metered which is controlled by the main switch contacts 58 and an independent internal circuit for the electro-magnet 52 which is controlled by both the contacts 56 and the contacts 72.

In operation, one or more coins are inserted in the chute 60, the first coin dropping as far as the lug 68 and forcing the insulating piece 70 outwardly to close the contacts 72. Assuming that the timing period initiated by any previously inserted coin has expired, the arm 24 will have rotated arm 32 on its pivot to the position in which the insulating piece 40 has closed contact 56 and opened contact 58. In this position of the device the electric circuit from the main line is completed to the terminal 98 and through the terminal 74, contacts 56, magnet 52 to terminal 96. Therefore, when contacts 72 are now closed by the first coin dropped into the chute the magnet 52 will be energized and armature 50 will be attracted. This will raise the right hand end of arm 48 carrying the arm 32 to such a height that the nose 38 of arm 32 will be raised above arm 24 so that the spring 36 can rotate arm 32 counter-clockwise to a position in which the nose 38 will lie slightly to the right of arm 24. This rotation of arm 32 by spring 36 lowers the contact arm 54 sufficiently to open contact 56 and close contact 58 even though the pivot of arm 32 be slightly raised at that moment due to the attraction of armature 50. Opening of contacts 56 and closing of contacts 58 completes an electric circuit connected to the motor 80 and switch 78 and if the switch 78 is closed, motor 80 will be caused to operate. As soon as contact 56 opens, the circuit to the magnet 52 is broken and the armature is released, thus permitting the nose 38 of arm 32 to drop down into the path of arm 24 in its next rotation, it being understood that arm 24 rotates counter-clockwise. When armature 50 is attracted the arm 64 is moved slightly to the right in Fig. 1 so that the lug 68 is withdrawn from support of the coin 62 and the lug 66 is projected into the coin chute to stop the fall of the next coin should there be another one in the chute. When the armature 50 is deenergized by the opening of the contact 56 (or by the opening of the contacts 72 due to the falling of coin 62, these two actions taking place practically simultaneously) the arm 64 moves back to the position shown in Fig. 1, withdrawing the lug 66 from underneath the upper coin and permitting it to drop down onto the lug 68 thus forcing the contacts 72 to close again. Closure of contacts 72 by the second coin, however, will not cause another actuation of magnet 52 at this time because contacts 56 are open. When the clock work has rotated gear 22 and with it the arm 24 for twenty-four hours, arm 24 again engages the nose 38 of arm 32 and raises spring contact 54. Upward movement of spring 36 again closes contacts 56 and opens contacts 58 to break the electric circuit leading to the motor 80 through switch 78. If there is a coin lying on the lug 68 in the coin chute 18 and contacts 72 are

closed by engagement of the coin with piece 70 the armature 50 will be immediately attracted and the operation of the device for controlling the completion of the electric circuit to motor 80 and switch 78 will repeat automatically for as many periods as there are coins in the chute. When all the coins are used up, the insulating piece 70 is moved into the coin chute 60 by action of the spring arms upon which contacts 72 are mounted, thus separating the contacts 72 and interrupting the circuit through the magnet 52. At the expiration of the predetermined period of time, the arm 24 will engage nose 38 and move arm 32 and cause insulating lug 40 to move upwardly to separate contacts 58, thus breaking the electric circuit through motor 80 and switch 78. This movement closes contacts 56 but armature 50 will not be attracted at this time due to the circuit through magnet 52 being broken at contacts 72. The device, however, remains in this position and may be rendered operative as soon as another coin is inserted in chute 60 to move insulating piece 70 outwardly from the chute 60 to cause closing of contacts 72. In this position of the device, arm 24 will be held against rotation by the nose 38 of arm 32. The slip connection between arm 24 and plate 26, however, will not stop the clock mechanism but will permit the gear 22 to go on rotating independently of the blocking of arm 24 by the arm 32 of the device.

In case the device to be metered draws a large current it may be desirable to substitute a snap acting switch for the switch 54, 56, and 58 which may take the form of any of the many examples of snap acting switches known in the art. Should it be desirable to use the same size and form of meter construction for use with many different devices to be metered, some of which are to be operated at different time rates from others, it is possible to provide for various predetermined periods of time of operation either by changing the ratio of gears 20-22 or by using a series of members 24 having one, two, three, or more arms depending on the time period desired.

It will thus be seen that I have provided a coin controlled service metering mechanism which will give a predetermined period of service for each coin inserted in the device wherein a plurality of coins may be inserted at once, the mechanism feeding them down as required by the meter and one wherein the electrically driven timing means is constantly running so that the meter also functions as a clock which is especially useful where the device is used to meter the service of an electric refrigerator, thus serving as a kitchen clock as well as a meter.

While the form of embodiment of the invention as herein disclosed, constitutes a preferred form, it is to be understood that other forms might be adopted, all coming within the scope of the claims which follow.

What is claimed is as follows:

1. In a coin controlled electric time switch, a constantly running constant speed motor, a circuit controller movable between two positions, a rotary member for moving the circuit controller, a friction clutch driving the member from the constant speed motor, means for blocking rotation of the member, said friction clutch permitting the motor to run while the member is blocked, a coin chute, and automatic means responsive to the deposit of a coin in the chute for removing the blocking means from the path of the member.

2. In a coin controlled electric time switch, a constantly running constant speed motor, a cir-

cuit controller movable between two positions, a 5 rotary member for moving the circuit controller, a friction clutch driving the member from the constant speed motor, means for blocking rotation of the member, said friction clutch permitting the motor to run while the member is blocked, a coin chute and means responsive to a coin in the chute for removing the blocking means from the path 10 of the member and for replacing the blocking means into the path of the member at a point where the member will contact the blocking means only after further rotation.

3. In a coin controlled electric time switch, an 15 internal circuit, an external circuit, a circuit controller movable between two positions for simultaneously controlling the external circuit and the internal circuit, a coin chute, a coin operated circuit controller for conjointly controlling the internal circuit and means including a solenoid in the 20 internal circuit for controlling the movement of coins in the chute.

4. In a coin controlled electric time switch, a 25 constantly running constant speed motor, an internal circuit, an external circuit, a circuit controller movable between two positions for simultaneously controlling the external circuit and the internal circuit, a coin operated circuit controller for conjointly controlling the internal circuit, a solenoid in the internal circuit, a timing member 30 adapted to be at times driven by the motor, and a single means operated by the solenoid for moving the first circuit controller and for initiating movement of the timing member.

5. In a coin controlled electric time switch, 35 a constantly running constant speed motor, an internal circuit, an external circuit, a circuit controller movable between two positions for simultaneously controlling the external circuit and the internal circuit, a coin operated circuit controller 40 for conjointly controlling the internal circuit, a solenoid in the internal circuit, a timing member adapted to be at times driven by the motor, a coin chute for passing coins into operative relation 45 with the coin operated circuit controller and a single means operated by the solenoid for moving the first circuit controller, for initiating movement of the timing member, and for controlling the passage of coins through the chute.

6. In a coin controlled electric time switch, 50 a constantly running constant speed motor, an internal circuit, an external circuit, a circuit controller movable between two positions for simultaneously controlling the external circuit and the internal circuit, a coin operated circuit controller

for conjointly controlling the internal circuit, a solenoid in the internal circuit, a timing member adapted to be at times driven by the motor, a coin chute for passing coins into operative relation with the coin operated circuit controller and a 5 single means operated by the solenoid for initiating movement of the timing member and for controlling the passage of coins through the chute.

7. In a coin controlled electric time switch, a 10 constantly running constant speed motor, a circuit controller movable between two positions, a rotary member for moving the circuit controller, coin controlled means for causing the rotary member to be driven by the motor and for simultaneously moving the circuit controller to a first 15 position, and means operated by the rotary member for moving the circuit controller to a second position after a predetermined time, said rotary member returning to starting position unidirectionally.

8. In combination, an electrical device to be 20 controlled having an electric circuit for receiving electric energy, an electric control circuit having switch means including coin controlled switch 25 means embodied therein, a continuously operating chronometrically controlled means powered independently of said switch means for opening the circuit of the electrical device and closing one of the switch means in the control circuit at the end of a predetermined period of time, a coin chute 30 capable of receiving a plurality of coins, and means responsive to the closing of said control circuit for releasing the lowermost coin in the chute and for retaining coins in the chute above the 35 lowermost coin.

9. In combination, an electrical device to be 40 controlled having an electric supply circuit provided with a circuit opening means for controlling the supply of electric energy, a coin chute capable of receiving a plurality of coins, a movable member having means for releasing the coins in the chute one at a time, said movable member being 45 provided with an armature arm, an electric control circuit having an electromagnetic means for attracting the armature arm of said movable member to operate the movable member to release the lowermost coin in the chute, said electric control circuit having coin controlled switch means, a motor and switch means operated thereby for controlling the energization of the electromagnetic means whereby said electrical device may be 50 operated.

RALPH L. TWEEDALE.
